AUTOMATIC SWITCH-LOCKING MECHANISM.

No. 926,211.

Specification of Letters Patent.

Patented June 29, 1909.

Application filed August 10, 1908. Serial No. 447,731.

To all whom it may concern:

Be it known that I, HARRY F. ROACH, a citizen of the United States, residing at St. Louis, Missouri, have invented a certain new and useful Improvement in Automatic Switch-Locking Mechanism, of which the following is a full, clear, and exact description, such as will enable others skilled in the art to which it appertains to make and use the same, reference being had to the accompanying drawings, forming part of this specification, in which—

Figure 1 is a diagrammatic view of a railway track structure provided with a switch locking mechanism constructed in accordance with my invention; Fig. 2 is an enlarged top plan view of the switch-points and my improved locking mechanism; Fig. 3 is an enlarged detail view showing the locking element and the tripping device in elevation, and the housing in which said parts are arranged in vertical section; Fig. 4 is a perspective view of a portion of the head rod or switch-point operating bar; Fig. 5 is an enlarged top plan view of the base plate that carries the housing in which the locking mechanism and tripping mechanism is arranged; Figs. 6 and 7 are cross sectional views of the wheel-operated members; and Fig. 8 is a top plan view of portions of the head rod, locking element and the tripping device.

This invention relates to automatic switch locking mechanisms, and particularly to that type in which the locking element is automatically tripped to release the switch-points and permit them to return to normal position to close the siding when a train passes from the main line onto the siding, or passes from the siding onto the main line.

The main object of my present invention is to provide an automatic switch-point locking mechanism that is strong and durable and which is of simple construction.

Another object is to provide a mechanism of the character described in which the locking element cannot be tripped until after the train has completely cleared the switch-points in passing from the siding onto the main line.

Another object is to provide a mechanism of the character described in which the tripping device for the locking element can be accurately adjusted. And still another object of my invention is to provide an automatic

switch-point locking mechanism comprising a locking element that is adapted to be tripped by the wheels of a train passing onto or off of the siding and which is so constructed that the tripping device for the locking element can be manually-operated.

Other objects and desirable features of my invention will be hereinafter pointed out.

I have herein illustrated my improved switch-point locking mechanism embodied in a railway track structure that comprises switch-points which are normally held in position to close the siding, a movable frog-point or tongue arranged at the intersection of the inside rails of two tracks, and means for causing said frog-tongue to move simultaneously with the switch-points. I do not wish it to be understood, however, that my improved locking mechanism is limited to such a structure for it can be used in a structure in which the switch-points have no connection whatever with the frog.

Referring to Fig. 1 of the drawings which is a diagrammatic view of a railway track structure provided with a switch-point locking mechanism constructed in accordance with my invention, 1 and 2, respectively, designate the inside rails of a main line and a siding, and 3 and 4, respectively, designate the switch-points of said rails, the switch-point 3 of the main line being normally held in position to close the siding by some suitable means, such, for example, as a spring arranged inside of a housing 6 and connected to a head rod or switch-point operating bar 7. It will be obvious, however, that other means than a spring could be employed for this purpose. The switch-point operating bar or head rod 7 is connected to the switch-points in such a manner that said switch-points can creep or travel longitudinally of the stationary rails alongside of which they extend without materially affecting said bar or head rod, the rod 7 herein shown being provided with pins 7^a that project through elongated slots 7^b in the bases of the switch-point rails. The other end of the head rod 7 is connected to an arm on a manually operated shaft 8 journaled in a switch-stand 9 located adjacent the switch-points. A movable frog-point or tongue 10 is arranged at the intersection of the inside rails of the main line and siding, and said frog-point is connected to the switch-point operating bar 7 by means of a system of links 110

11 and bell crank levers 12 which cause said tongue to move whenever the head rod 7 is operated.

The switch-point locking mechanism comprises a locking element arranged in a housing A located adjacent the switch-points and a tripping device also arranged in said housing and adapted to be moved in one direction by yielding means and in the opposite direction by wheel-operated members 14 and 14^a arranged alongside of the outside rail 2^a of the siding. The switch-point operating bar 7 passes through the housing A, and the locking element which is arranged inside of said housing, consists of a pivotally mounted pawl or dog 15 that is adapted to move downwardly into locking position whenever the head rod 7 is moved in the direction of the arrow *a* in Fig. 2 to open the siding, said head rod being provided with a roller 16 behind which the dog 15 drops when the siding switch-point 4 engages the outside rail 1^a of the main line. Any suitable shoulder or abutment on the head rod 7 would, of course, perform the same function as the roller 16, but I prefer to use a roller so as to eliminate as much as possible any friction between the locking element and its coöperating abutment on the head rod 7.

As shown in Fig. 4, the head rod 7 has a member 17 secured to the upper side thereof and said member is provided with ears 16^a in which the pivot pin 16^b of the roller 16 is journaled. Said member 17 is also provided with ears 18 that project downwardly below the bar 7 so as to form bearings for the pivot pin of a roller 19 located underneath the bar 7, as shown in Fig. 3. The locking element or pivotally mounted dog 15 normally rests upon an inclined face on the member 17 connected to the head rod 7, and when said rod is moved in the direction of the arrow *a* in Fig. 2, as previously stated, said locking element drops into operative position to lock the head rod 7 and thus prevent the switch-points from returning to their normal position until said locking element is tripped.

The means herein shown for tripping said locking element consists of a bifurcated arm 20 on a rock shaft 21 that extends transversely of the housing A. The rock shaft 21 is provided at one end with an arm 22 to which a link 23 is connected, and the opposite end of said link is fastened to the wheel-operated member 14 arranged adjacent the outside rail 2^a of the siding. A plunger 24, which is arranged inside of the housing A, is connected to the bifurcated arm or tripping device 20, and said plunger passes through a bearing 25 having trunnions 26 that project laterally into elongated slots or recesses 25^a in the side walls of the housing A, as shown in Fig. 5. The plunger 24 is provided with

an adjustable stop consisting of one or more nuts 27 that engage the bearing 25 and limit the movement of the plunger in one direction, and one or more coiled springs 28 are arranged on said plunger between the bearing 25 and a collar 29 on the plunger. The collar 29 butts against stops 29^a on said plunger and said stops can be adjusted to vary the tension of said springs.

When the wheel-operated members 14 and 14^a are depressed, as hereinafter described, the rock shaft 21 will be rocked and thus move the plunger 24 in the direction indicated by the arrow *b* in Fig. 3, thereby placing the springs 28 under compression, and when said wheel-operated members are released the springs 28 will expand and thus move the plunger in the opposite direction, thereby causing the tripping device 20 to trip the locking element 15. Instead of having the tripping device 20 coöperate directly with the locking element 15 I prefer to provide said locking element with a pivotally mounted pawl 15^a that normally lies above the tripping device, as shown in Fig. 3, said pawl being adapted to move into position to be engaged by a friction roller 20^a on the tripping device when the locking element drops into operative position and the tripping device is retracted. The pawl 15^a is arranged in a slot 15^b formed in the locking element, as shown in dotted lines in Fig. 3, and when the head rod 7 is thrown to open the siding said pawl will pass between the sides or jaws of the bifurcated tripping device 20 when the locking element 15 drops into operative position. The pawl remains in this position until the plunger 24 is moved in the direction of the arrow *b* in Fig. 3 to retract the tripping device, and when said plunger moves and thus carries the tripping device away from the head rod, said pawl will swing on its fulcrum so as to not interfere with the movement of the tripping device. As soon as said tripping device has cleared the pawl 15^a said pawl will drop downwardly so that its free end will be in the path of movement of the tripping device 20 when said tripping device is returned to normal position by the expansion of the springs 28, the bottom of the slot 15^b limiting the movement of the pawl. The object of providing the locking element with a pawl 15^a is to permit the tripping device 20 to retract without affecting the position of the locking element and still be in position to trip said locking element when the springs 28 expand to move said tripping device forwardly.

The housing A in which the locking element and tripping device are arranged is of novel construction and is so designed that snow, ice, or any other foreign matter cannot enter same and thus interfere with the movements of the members which it incases. The

housing A is formed in sections that are detachably connected together so that the elements arranged inside of same will be accessible, and said housing is carried by a 5 base plate 30 that is connected to the track ties. This base plate is provided with an integral portion 31 of approximately channel-shape in cross section in which the plunger 24 and tripping device 20 are arranged, said 10 channel-shaped portion being provided at one end with an end wall 32. A removable cap or cover 33, which forms the top of the housing, is connected to the channel-shaped portion 31 by fastening devices 34, and at 15 one end of said channel-shaped portion is an approximately inverted U-shaped part 35 in which the locking element 15 is arranged, the pivot pin of said locking element passing through the side walls of said U-shaped part.

20 A door 36 of approximately the same cross sectional shape as the part 35 coöperates therewith to completely inclose the locking element 15, and said door is carried by a hinged member provided with ears 37 that 25 are pivotally connected to bifurcated ears 38 on the base plate by means of bolts or other suitable fastening devices 39. The door 36 is preferably provided with a flange 40 that laps over the edge portion of the inverted 30 U-shaped part 35 so as to produce a tight joint, and the hinged member which carries said door is also provided with a flange 40 that laps over the stationary member on the base plate with which said hinged member 35 coöperates. The door 36 and the part 35 are provided with coöperating perforated ears 41 through which a padlock 42 or other suitable fastening device can be inserted, as shown in Fig. 5, to lock the lid. The base 40 plate 30 is provided with a transversely extending closed guideway through which the switch-operating bar 37 passes, said guideway being formed by a stationary member 43 on the base plate and the hinged member 45 that carries the door 36.

When the door is closed the hinged member on which it is mounted and the stationary part 43 on the base plate coöperate with each other to form a closed guideway that 50 projects laterally from each side of the housing in which the locking element and tripping device are arranged.

The rock shaft 21, to which the tripping device 20 is connected, is journaled in bearings 44 on the underneath side of the base plate, and said base plate is provided with a slot 45 through which said tripping device passes, as shown in Fig. 3. As shown clearly in Fig. 3, the closed guideway 43 through 60 which the head rod 7 passes is so proportioned that the head rod can move laterally without binding on the walls of said guideway. The head rod is connected to the switch-points by a slot and pin connection, as previously stated, so that the switch-

points can creep longitudinally without affecting the head rod but in case the head rod does creep or move longitudinally of the track, this would not interfere with the locking mechanism for the locking element 15 70 and the tripping device 20 are mounted on fixed fulcrums and the head rod which is interposed between said parts can shift or move laterally without causing the locking element to change its position relatively to 75 the head rod. In other words, creepage of the track rails does not affect the locking mechanism for the locking element consists of a pivotally mounted member that rests on the head rod which is so designed that it 80 can move laterally or creep slightly with the rails.

The wheel-operated members 14 and 14^a consist of bars that are pivotally connected to the upper ends of short links 46, the lower 85 ends of which are pivotally connected to clips 47 which are fastened to the outside rail 2^a of the siding, each of said clips being provided with a flange 48 that projects underneath the base of said rail and a vertical 90 web 49 that is connected to the vertical web of said rail by fastening devices 50, as shown in Fig. 6. The bars 14 and 14^a normally lie above the head of the rail 2^a, and the links 46 on which said bars are mounted, are so 95 disposed that the bar 14 will be depressed and moved longitudinally in the direction of the arrow c in Fig. 1 by the wheels of a train that is passing from the main line onto the siding, and the bar 14^a will be depressed 100 and moved longitudinally in the direction of the arrow d in said figure by the wheels of a train that is passing from the siding onto the main line. One end of the bar 14 is fastened 105 to a lever 51 which is pivotally connected at its outer end to a stationary support, and the adjacent end of the bar 14^a is connected to a lever 52 which is pivoted at approximately its center to a support. A link 53 connects the outer end of the lever 52 to the intermediate portion of the lever 51, as shown in Fig. 1, so that whenever the bar 14 is depressed 110 the bar 14^a will be depressed and vice versa, said bars always moving longitudinally in 115 opposite directions.

As previously stated, the depression of either of the bars 14 or 14^a compresses the springs 28 which actuate the tripping device that moves the locking element and whenever said bars are released said springs will 120 expand and thus cause the tripping device 20 to disengage the locking element 15 from the switch-point operating bar 7 so that said bar can return to normal position and thus close the siding.

To eliminate the possibility of the locking element 15 being released until a train that is passing from the siding onto the main line has completely cleared the switch-points, I have arranged a comparatively short wheel- 130

operated member 54 along the outside rail 2^a adjacent the switch-points, said wheel-operated member 54 being long enough so that it extends for a short distance along the 5 main line rail in front of the switch-points. This wheel-operated member 54 also consists of a bar pivotally connected to the upper ends of short links 55 that have their lower ends connected to clips on the rail 2^a 10 but said links are so constructed that the bar 54 will normally lie flush with the tread of the rail 2^a. The bar 54 is provided with a laterally projecting lug 56 through which a rod 57 passes, said rod being connected at 15 one end to the arm 22 on the rock shaft 21 which carries the tripping device. The rod 57 is provided on one side of the lug 56 with a rigid collar 58, and a coiled spring 59 is interposed between the other side of said lug 20 and an adjustable stop 60 on the rod, as shown in Fig. 2.

When a train passes from the siding onto the main line the wheel-operated members 14 and 14^a will be depressed and thus rock the 25 shaft 21 to which the tripping device 20 is connected, the movement of said shaft pulling the rod 57 in the direction of the arrow *e* in Fig. 2 and thus causing the wheel-operated member 54 to rise and move longitudinally in 30 the direction of said arrow. The links which carry the wheel-operated member 54 are so constructed that they will move completely over into an opposite inclined position when the rod 54 is pulled in the direction of the 35 arrow *e* in Fig. 2 so that the wheel-operated member 54 will lie flush with the tread of the rail 2^a in its shifted position. When the wheels pass off the wheel-operated member 14 and thus release said member, the springs 40 28 would expand and thus cause the tripping device 20 to disengage the locking element 15 from the head rod if it were not for the wheel-operated member 54, but as said member is held depressed by the wheels that pass over 45 it, it will be impossible for the springs 28 to expand until said member 54 is released, due to the fact that the lug 56 on said member bears against the collar 58 on the rod 57 which is fastened to the shaft 21 that carries 50 the tripping device. The wheel-operated member 54 is of such length and is so arranged relatively to the wheel-operated member 14 that when the rear wheel of a truck releases the member 14 the forward 55 wheel of the truck will be engaging the member 54 and will be traveling over said member until the rear wheel of the truck engages said member. As soon as the wheels have completely cleared the switch-points and have 60 released the wheel-operated member 54 the springs 28 will expand and thus cause the device 20 to trip the locking element 15 so that the switch-points can return to normal position to close the siding, the wheel-operated 65 member 54 being shifted back to its normal

position when the wheel-operated members 14 and 14^a return to normal position.

When a train passes from the main line onto the siding the wheel-operated members 14 and 14^a will be depressed and the spring 59 will be compressed, due to the fact that the member 54 is prevented from rising and moving into its shifted position until after the wheels have passed off said member. The member 54 is moved into its shifted position 70 by the expansion of the spring 59 as soon as the wheels have released said member and when the wheel-operated members 14 and 14^a return to normal position the rod 57 will shift the wheel-operated member 54 back to 75 normal position.

The head rod or switch-operating bar 7 is adapted to be operated manually to open the siding by a switchman standing at the switch-stand 9 but, if desired, said bar 7 can be operated by a person stationed in a switch-tower located some distance from the switch-points. I have illustrated such a construction in Fig. 2 wherein the reference character 61 indicates a bell crank lever having one of 80 its arms connected to the head rod 7 and its other arm connected to a rod 62 that leads to a switch-tower, not shown, located some distance from the switch-points. In Fig. 2 I have also shown manually-operated means 85 for causing the tripping device 20 to release the locking element so that it will not be necessary for a train to pass onto or off of the siding to release the head rod 7. Said means consists of a rod 63 connected to the wheel-operated member 14 and leading to a switch-tower so that the operator in the tower can pull said rod and thus compress the springs 28 and then release said rod and permit said 90 springs to expand and actuate the tripping device.

An automatic switch-locking mechanism of the construction above described comprises few parts so that it is not liable to get out of order, the parts which comprise said mechanism are so designed that the mechanism is strong and durable, the movable parts which constitute the automatic locking means are all inclosed so that they cannot become clogged with snow, ice, or any other 100 foreign substance, and the housing which incloses said parts is so designed that the parts inside of same are accessible. The tripping device that disengages the locking element can be accurately adjusted by manipulating the nuts 27, and the tension of the springs 28 which move said tripping device into operative position, can be varied by manipulating the nuts or adjustable stops 29^a for the collar 29.

The elongated slots or recesses 25^a in the side walls of the housing A into which the trunnions on the bearing 25 project, permit said bearing to move longitudinally when the wheel-operated members 14 and 14^a are first 105 110 115 120 125 130

engaged by the wheels of the train so that said bearing is not subjected to a sudden shock or jar, and as the head rod 7 is provided with a roller 19 which travels over the 5 base plate 30 and also a roller 16 that is engaged by the locking element, said parts will always move freely. The tripping device which releases the locking element can either be operated manually or by the wheels of a 10 train that passes onto or off of the siding and as the wheel-operated member 54 prevents the tripping device from moving into operative position until after the wheels of a train passing from the siding onto the main line 15 has completely cleared the switch-points, it will be impossible for the switch-points to close prematurely. Consequently, the spring 5 will not be interrupted after the lock has been released, thereby assuring the clos- 20 ing of the track. If the switch-points were released prematurely the spring 5 would expend half of its energy and the wheels of the truck going through the switch would cause the switch to remain open, probably one and 25 one-half inches, the spring thereafter completing its throw to close the siding.

With a construction of the character above described, the spring or other source of energy used to close the switch cannot be interrupted but completes its entire work in a 30 single operation instead of two operations.

Having thus described my invention, what I claim as new and desire to secure by Letters Patent is:

35 1. An automatic switch locking mechanism, comprising means for locking the switch-points in position to open the siding, a device for tripping said means to release the switch-points, means adapted to be operated by a 40 train on the siding for setting said tripping device or moving it into an operative position, and means for preventing said tripping device from tripping the switch-point locking means until a train passing from the siding onto the main line has completely cleared 45 the switch-points; substantially as described.

2. An automatic switch locking mechanism, comprising switch-points, means for normally holding said switch-points in position to close the siding, means for moving said switch-points into position to open the siding, automatically operated means for locking the switch-points after they have been 50 moved to open the siding, a tripping device for releasing the switch-points from said locking means, means adapted to be operated by a train on the siding for setting said tripping device or moving it into an operative 55 position, and a wheel-operated member for preventing said tripping device from releasing the switch-point locking means until a train passing from the siding onto the main line has completely cleared the switch- 60 points; substantially as described.

3. An automatic switch locking mechanism, comprising switch-points, means for normally holding said switch-points in position to close the siding, means for moving said switch-points into position to open the siding, 70 automatically operated means for locking the switch-points after they have been moved to open the siding, a tripping member adapted to operate said locking means to release the switch-points, means adapted to be 75 operated by a train on the siding for setting said tripping member in an operative position, and a wheel-operated member arranged adjacent the switch-points and operatively connected to said tripping member so as to 80 prevent same from actuating the switch-point locking means until a train has completely cleared the switch-points; substantially as described.

4. An automatic switch locking mechanism 85 provided with a locking element that is adapted to move into position to lock the switch-points after they have been moved to open the siding, a tripping device for moving said locking element into an inoperative position, wheel-operated members adapted to be 90 operated by a train on the siding for causing said tripping device to become operative, and means for preventing said tripping device from actuating the locking element 95 when a train is passing from the siding onto the main line; substantially as described.

5. An automatic switch locking mechanism provided with a locking element that is adapted to move into an operative position 100 when the switch-points have been moved into position to open the siding, a yieldingly actuated tripping device for moving said locking element into an inoperative position, wheel-operated members for storing up 105 energy in the yielding means that operates said tripping device, and means for preventing the tripping device from moving the locking element into an inoperative position until after a train has completely cleared the 110 switch-points in traveling from the siding onto the main line; substantially as described.

6. An automatic switch-locking mechanism provided with a locking element that is adapted to move into an operative position 115 when the switch-points have been shifted to open the siding, a tripping device for moving said locking element into an inoperative position, yielding means for actuating said tripping device, wheel-operated members 120 arranged adjacent one of the rails of the siding and adapted to be depressed by the wheels of a passing train for storing up energy in said yielding means, a wheel-operated member arranged adjacent one of the switch-points 125 and extending for a short distance in front of said switch-point, and means controlled by said last-named wheel-operated member for preventing the tripping device from actuating the locking element during the time a 130

wheel is passing over said wheel-operated member; substantially as described.

7. An automatic switch locking mechanism, comprising a locking element that is adapted to move into operative position to lock the switch-points after said switch-points have been shifted to open the siding, a rock shaft provided with a tripping device that is adapted to move said locking element into an inoperative position, yielding means which normally holds said tripping device in a certain position, means for moving said rock shaft to store up energy in said yielding means, a wheel-operated member arranged adjacent the switch-points, and a connection between said wheel-operated member and said rock shaft which holds said yielding means under compression until after a train has passed from the siding onto the main line; substantially as described.

8. An automatic switch locking mechanism provided with a locking element that is adapted to move into position to lock the switch-points when said switch-points have been shifted into a certain position, a tripping device, and a movable member on the locking element which occupies an inoperative position relatively to the tripping device when said device is in its idle position, but which is adapted to move into position to be engaged with said tripping device when said tripping device is actuated; substantially as described.

9. An automatic switch-locking mechanism provided with a switch-point operating bar, a locking element coöperating with said bar, a tripping device, and a movable member on said locking element which is adapted to be engaged by said tripping device to move said locking element into an inoperative position; substantially as described.

10. An automatic switch locking mechanism provided with a locking element, a pivotally mounted tripping device, and a movable member on the locking element normally resting on said tripping device and adapted to move into position to be engaged by said tripping device when same is actuated; substantially as described.

11. An automatic switch locking mechanism, provided with a switch-point operating bar, a locking element normally resting on said bar and adapted to move in position to lock same when said bar is shifted in one direction, a tripping device, a pivotally mounted pawl on said locking element normally resting on said tripping device and adapted to move into position to be engaged by said tripping device when same is actuated, and means for actuating said tripping device; substantially as described.

12. An automatic switch-locking mechanism provided with a switch-point operating bar, a pivotally mounted locking element adapted to drop into position to lock said

bar when it is shifted in one direction, a pivotally mounted tripping device arranged adjacent said locking element, and a pawl arranged in a slot in said locking element and adapted to be engaged by said tripping device when it is moved in one direction; substantially as described.

13. An automatic switch locking mechanism provided with a switch-point operating bar, a pivotally mounted locking element adapted to drop into position to lock said bar when it is shifted in one direction, a pawl carried by said locking element, and a pivotally mounted tripping device arranged adjacent the locking element and provided with a bifurcated portion into which said pawl moves when the locking element drops into operative position; substantially as described.

14. An automatic switch locking mechanism provided with a switch-point operating bar, a member connected to said bar and provided with a roller that is arranged underneath the bar, a second roller on said member, a locking element adapted to drop behind said last-mentioned roller when the bar is moved in one direction, and means for tripping said locking element to release said bar; substantially as described.

15. An automatic switch locking mechanism provided with a locking element that is adapted to move into position to lock the switch-points when they are shifted in a certain direction, a tripping device for disengaging said locking element, means for actuating said tripping device, and adjustable means for limiting the movement of said tripping device; substantially as described.

16. An automatic switch-locking mechanism provided with a locking element that is adapted to move into position to lock the switch-points when they are shifted in a certain direction, a device for tripping said locking element, a spring for moving the tripping device into position to trip said locking element, means for storing up energy in said spring, and means for varying the tension of said spring; substantially as described.

17. An automatic switch locking mechanism provided with a locking element, a tripping device therefor, a plunger connected to said tripping device and provided with a collar, a bearing through which said plunger passes, a spring interposed between said bearing and the collar on said plunger, and a stop on said plunger adapted to engage said bearing to limit the movement of the plunger in one direction; substantially as described.

18. An automatic switch locking mechanism provided with a locking element, a tripping device therefor, a plunger connected to said tripping device and provided with a collar, a bearing through which said plunger passes, a spring interposed between said

bearing and the collar on said plunger, an adjustable stop on the plunger adapted to engage the bearing and limit the movement of the plunger in one direction, and means for changing the position of the collar on said plunger to vary the tension of said spring; substantially as described.

19. An automatic switch locking mechanism comprising a locking element, a pivotally mounted tripping device, a plunger connected to said tripping device and provided with a collar, a pivotally mounted bearing through which said plunger passes, a spring arranged on said plunger between said bearing and the collar on the plunger, a stop on the plunger for limiting its movement in one direction, and means for moving said tripping device to store up energy in said spring; substantially as described.

20. An automatic switch locking mechanism provided with a locking element, a tripping device, a plunger connected to said tripping device and provided with a collar, a bearing through which said plunger passes, trunnions on said bearing that project into elongated slots or recesses in a stationary member, a spring arranged between the collar and the plunger and the bearing through which the plunger passes, a stop on said plunger coöperating with said bearing to limit the movement of the plunger in one direction, and wheel-operated members operatively connected to the tripping device to move it and thus store up energy in said spring; substantially as described.

21. An automatic switch locking mechanism comprising a locking element, a tripping device therefor, a rock shaft to which said tripping device is connected, a plunger connected to said tripping device, a pivotally mounted bearing through which said plunger passes, a spring arranged on said plunger between said bearing and the collar on the plunger, and a wheel-operated member operatively connected to said rock shaft for moving the tripping device in one direction and thus store up energy in said spring; substantially as described.

22. An automatic switch locking mechanism provided with a switch-point operating bar, a base plate provided with a guideway through which said bar passes, a housing on said base plate, a locking element arranged in said housing and adapted to pass through an opening in said guideway to engage the switch-point operating bar when it is moved in one direction, and mechanism arranged inside of said housing for tripping said locking element; substantially as described.

23. An automatic switch locking mechanism provided with a switch-point operating bar, a base plate provided with a closed housing through which said bar passes, a housing on said base plate consisting of a number of sections that are detachably connected to

gether, a locking element arranged in said housing for locking said switch-point operating bar, and tripping mechanism arranged in said housing; substantially as described.

24. An automatic switch locking mechanism provided with a switch-point operating bar, a base plate provided with a closed guideway through which said bar passes, a channel-shaped portion on said base plate provided at one end with an inverted U-shaped part, a pivoted locking element arranged in said inverted U-shaped part, a hinged lid coöperating with said part to incase the locking element, tripping mechanism arranged in the channel-shaped portion of the base plate, and a removable top or cover for said channel-shaped portion; substantially as described.

25. An automatic switch locking mechanism provided with a switch-point operating bar, a base plate having a closed guideway through which said bar passes, a closed housing on said base plate, a locking element arranged in said housing and adapted to pass through an opening in said guideway for locking said switch-point operating bar, a rock shaft journaled in bearings on the underneath side of the base plate, and a tripping device on the rock shaft projecting through an opening in the base plate; substantially as described.

26. An automatic switch locking mechanism provided with a locking element that is adapted to move into position to lock the switch-points after they have been shifted to open the siding, a tripping device for moving said locking element into an inoperative position, wheel-operated members for causing said tripping device to become operative, and manually-operated means for actuating said wheel-operated members; substantially as described.

27. An automatic switch locking mechanism comprising a locking element adapted to move into position to lock the switch-points after they have been shifted to open the siding, a tripping device for moving said locking element into an inoperative position, and mechanism whereby said tripping device can be operated either manually or by the wheels of a train passing over the siding in either direction; substantially as described.

28. An automatic switch-locking mechanism, comprising switch-points, a head rod, a connection between said rod and switch-points which is so arranged that the switch-points can creep without affecting the head rod, a locking element coöperating with said rod, and means for tripping said locking element; substantially as described.

29. An automatic switch locking mechanism, comprising switch-points, a head rod for actuating said switch-points, a locking element pivotally connected to a stationary support and normally resting on said head

- rod, and a tripping device pivotally connected to a support and adapted to engage said locking element to release the head rod; substantially as described.
- 5 30. An automatic switch-locking mechanism, comprising switch-points, a head rod, a guideway through which said rod passes, said guideway being of such dimensions that the head rod can move or shift laterally with-
10 out binding, a locking element coöperating

with said rod, and a tripping device adapted to engage said locking element; substantially as described.

In testimony whereof I hereunto affix my signature in the presence of two witnesses, 15 this sixth day of August 1908.

HARRY F. ROACH.
